UNITED STATES PATENT OFFICE.

MORRIS B. OKUN, OF CHICAGO, ILLINOIS.

BED-RAIL FASTENER.

1,303,109.

Specification of Letters Patent.

Patented May 6, 1919.

Application filed January 19, 1917. Serial No. 143,226.

To all whom it may concern:

Be it known that I, MORRIS B. OKUN, a citizen of the United States, residing at Chicago, in the county of Cook and State of Illinois, have invented a certain new and useful Improvement in Bed-Rail Fasteners, of which the following is a full, clear, concise, and exact description, reference being had to the accompanying drawings, forming a part 10 of this specification.

My invention relates to bed rail fasteners and has for its object the provision of an improved bed rail fastener which may be readily made reversible, and which is so made that it can be easily placed in position, locking itself in place. The side rail, for instance, may be placed in position and mounted upon the two corner posts of the bed. If then it is desired to use the side rail 20 in its reverse position with the flange below instead of on top, then the entire side rail is turned end for end, the fastening devices being of such a character that the side rail is then supported in its reverse position in exactly the same manner that it was held in place when in its original position.

My invention further contemplates improved means for securing the side rail fastener to the bed post. The invention is 30 applicable both to square, round, or posts formed in other ways.

The above and other features will be more clearly apparent from the detailed description of the device which I will now give in connection with the accompanying drawings, in which—

Figure 1 is a side view of a device constructed in accordance with my invention;

Fig. 2 is a top view thereof;

Fig. 3 is a sectional view on line 3—3 of Fig. 1;

Fig. 4 is a view similar to Fig. 1 showing however the rail and its extremity supporting structure as being made of one and the same piece;

Fig. 5 is a sectional view on line 5—5 of Fig. 4;

Fig. 6 is a side view similar to that of Fig. 1 looking at the opposite side, however, to that of Fig. 1; and

Fig. 7 is a fragmentary view somewhat similar to Fig. 2 showing the device as applied to a round instead of a rectangular corner post.

In the drawings I show a bed corner post 10 to which my bed rail fastener 11 is se-

cured. This bed rail fastener is held in position upon the post through the agency of the U-shaped clamping element 12. This U-shaped clamping element has screw threaded extensions 13 and 14 projecting from its plate-shape portion. The clamping element 12 is inserted through the holes in the bed post, as shown more clearly in Figs. 1 and 2, the said clamping element then also passing through the holes in the fastener 11, the two being held securely together by means of the nuts 17 and 18.

In Fig. 7, I show a round corner post 19 being held by the rounded clamping element 20, otherwise similar to the clamping element 12, holding the fastener 21 in position through the agency of the nuts 22. The fastener is made of a single piece of metal consisting of the end portion 23, the side portion 24, and the bent over top portion 25. The top portion 25 furthermore has a downwardly bent apron 26 and the side portion 24 has the inwardly bent strengthening rib 27. The end portion 23 likewise has the forwardly extending bracket 28 having an outward extension 29 to which the end rail 30 is riveted, as at 31, this end rail also being riveted as at 32 to the top wall 25 of said fastener. The side wall 24 has a slot 33 cut therein to thereby form an upwardly projecting tongue 34. The side wall 24 likewise has a projecting pin 35 fastened thereto, the pin 35 and apron 26 together with the said tongue 34 cooperating to hold the side rail 36 in position. This side rail may be of the customary angle iron shape having the horizontally extending flange 37.

In order to adapt the side rail for proper mounting upon the fastener 11, I rivet to this side rail an angular supporting element 38, this being riveted as shown at 39. This angular supporting element has a loop 40 pressed outwardly, which loop is adapted to encircle the tongue 34, the tongue passing between the loop 40 and the upper and lower remaining bridge pieces 41 and 42 respectively of this supporting element. The extending portion 43 of this supporting element then abuts the apron 26 and pin 35. The tongue 34 is tapered upwardly so that a projection 44, which remains in its original position, not being punched outwardly when the loop 40 is pressed out, can cooperate therewith to lock the supporting element in position upon this tongue. The supporting element thus abuts the elements 26 and 35.

and is clamped in position by the projection 44, all coöperating with the tapering tongue 34.

Now if the side rail of Fig. 1 with the 5 horizontal flange 37 is to be used in a reverse manner, then this side rail is turned end for end, the angle section 36 remaining in its plane until the supporting elements at the opposite extremities have been 10 reversed in position relative to the two corner posts of the bed. In this position the structure is up side down as shown in Fig. 4. It will be noted that the supporting element 38 coöperates with the fastener 11 just 15 exactly the same as it did when in its reverse position of Fig. 1.

A very simple reversible bed rail fastener is thus provided adapted to lock itself in position and being amply braced. The inwardly extending flange 27 lends rigidity to the structure. It is further of course obvious that if the side rail 36 were made of an angle piece having wider flanges as shown at 36^a in Fig. 4, that then the side 25 rail itself is punched at its extremities into the shape of the supporting element 38, thus obviating the necessity of having three pieces for this structure. This of course depends merely on questions of facilitating 30 the manufacture and the cost of materials.

From what has been thus described the nature of my invention will be readily clear to those skilled in the art.

Having however thus described my invention, what I claim as new and desire to secure by Letters Patent is:

1. A structure of the character described comprising a bed rail fastener having a wide, flat supporting tongue, whose wide face extends in the direction of the length of the side rail, a side rail, and means including a laterally disposed loop carried at the opposite extremities of said side rail to coöperate with said tongue, said tongue coöperating both with the means at one extremity of said side rail to hold said side rail in position, and with the means at the opposite extremity of said rail to hold said side rail in position when said side rail is 50 swung end for end and inverted, to thus hold said side rail in either one of two given positions.

2. A structure of the character described comprising a bed rail fastener having a tapering wide, flat supporting tongue whose wide face extends in the direction of the length of the side rail, a side rail, and means including a laterally disposed loop carried at the opposite extremities of said side rail 60 to coöperate with said tongue, said tongue coöperating both with the means at one extremity of said side rail to hold said side

rail in position, and with the means at the opposite extremity of said rail to hold said side rail in position when said side rail is 65 swung end for end and inverted, to thus hold said side rail in either one of two given positions, said fastener having an abutment to coöperate with said means, and each of said means having a clamping element to coöperate with said tongue, said fastener having a strengthening rib.

3. A structure of the character described comprising a bed rail fastener having a tapering wide, flat supporting tongue whose 70 wide face extends in the direction of the length of the side rail, a side rail, and means including a laterally disposed loop carried at the opposite extremities of said side rail to embrace said tongue, said tongue coöperating both with the means at one extremity of said side rail to hold said side rail in position, and with the means at the opposite extremity of said rail to hold said side rail in position when said side rail is 75 swung end for end and inverted, to thus hold said side rail in either one of two given positions, said fastener having an abutment to coöperate with said means, and each of said means having a clamping element to 80 coöperate with said tongue, said fastener having a strengthening rib, and said fastener being made of a single piece of material.

4. A structure of the character described 95 comprising a bed rail fastener having a wide, flat taper supporting tongue, a side rail, said side rail having a laterally struck-out portion of the metal adapted to embrace said tongue to hold the fastener and side 100 rail together, said side rail having a portion extending into the path of the supporting tongue and adapted to act upon an edge thereof to lock the fastener and rail.

5. A structure of the character described 105 comprising a bed rail fastener having a wide flat supporting tongue, a side rail having a laterally struck-out portion of metal at each end to embrace said tongue, said tongue coöperating with the struck-out portion at 110 one extremity of said side rail to hold said side rail in position and with the struck-out portion at the opposite extremity of said side rail to hold said side rail in position when said side rail is swung end for end, to 115 thus hold said side rail in either one of two given positions.

In witness whereof I hereunto subscribe my name this thirteenth day of January, A. D. 1917.

MORRIS B. OKUN.
